UNITED STATES PATENT OFFICE.

JOHN G. CAPSTAFF AND NEWTON B. GREEN, OF ROCHESTER, NEW YORK, ASSIGNEES TO
EASTMAN KODAK COMPANY, OF ROCHESTER, NEW YORK, A CORPORATION OF
NEW YORK.

COLOR PHOTOGRAPHY.

Application filed March 25, 1921. Serial No. 455,706.

To all whom it may concern:

Be it known that we, JOHN G. CAPSTAFF and NEWTON B. GREEN, subject of the King of Great Britain, citizen of the United States of America, respectively, residing at Rochester, in the county of Monroe and State of New York, have invented certain new and useful Improvements in Color Photography, of which the following is a full, clear, and exact specification.

This invention relates to color photography and more particularly to a process involving the use of a transparent support or base upon the opposite sides of which are registered complementary color images.

In the patent to Capstaff No. 1,196,080, August 29, 1916, the steps of such a process are outlined. It has been found, when the registering images upon the opposite sides 20 of a transparent support have been dyed in complementary colors, to be a delicate operation to balance properly the intensity of the colors so as to produce satisfactory reproductions of the original objects. The object 25 of this invention is to modify this color balance or ratio after dyeing so as to correct any apparent errors.

In the process as outlined in the above mentioned patent, gelatine layers upon opposite surfaces of the support are differentially tanned in accordance with the photographic images, and then submitted to complementary dye baths. After dyeing, the emulsion is submitted to an acid alum bath 30 which, we believe, precipitates or fixes the dye in place in the gelatine. The registering images made in accordance with the process mentioned, therefore, comprise as we believe, dye images precipitated in place in the gelatine by the action of this bath. In stating 35 the nature of the dye image, we do not wish to bind ourselves to any theory that may possibly be disproved at some future time. We have discovered that color images 40 made in the manner heretofore described can be treated as herein fully set forth and we shall describe various equivalent steps that may be used. It is possible that in addition to a precipitated dye image there may be 45 some combination between the dye and the colloid of the emulsion, but neither the establishment nor disproof of such a relation 50 would alter the facts which we have discovered. The color ratio, i. e., the relative 55 intensity of coloring upon the opposite sur-

faces, is largely a matter for the judgement of the operator, and after the record is completed, it has hitherto been possible to correct this color ratio only by entirely decolorizing one of the emulsions and resubmitting 60 it to a dye bath. This is true also of other processes in which the images are composed of mordanted dyes, i. e., dyes adsorbed to particles in the gelatine layers. We have discovered, however, that it is possible to 65 correct an imperfect color ratio. This incorrect ratio necessarily means that one side is more intense than the other, and it is possible, by submitting the too intensely colored side to a bath which tends to release 70 the dye, to reduce the intensity of its color to a point where it will properly balance the color of the other side.

In order to point out more fully one way in which this method may be practiced, 75 reference will now be made to the accompanying drawings in which the same reference characters refer throughout to the same parts, and in which

Fig. 1 is a plan of an apparatus which 80 may be used;

Fig. 2 is a front elevation thereof;

Fig. 3 shows the relation of two of the 85 parts; and

Fig. 4 is a perspective detailed view of the guide for the film.

Upon a table 1 is supported on axis 2 a rotatable reel 3 carrying a supply roll of motion picture film 4, the film having been so treated as to bear complementary color 90 images of the type described. A take-up reel 5 is driven by the motor 6 which also drives a buffing roller 7. This buffing roller has felt surfaces and is adjustable vertically to three positions, being controlled by means 95 of a pedal 8, two positions of the pedal being shown in dotted lines. The roller is shown in its uppermost position in Fig. 2. The film 4 passes in front of an illuminating box 9 and the operator inspects it as it passes the 100 window of this box, judging whether or not the color ratio is correct. The film normally passes from said inspection window to the take-up reel, being guided by rollers 10 and passing through a drying cabinet 11. The 105 roller 7 is normally in middle position during such action and the film passes untwisted directly over the inspection window to the drying chamber as indicated in dotted lines. During such passage it traverses a guide 12 110

shown in detail in Fig. 4, comprising a frame at each end 13 in which are guide rollers 14. A handle 15 is also furnished on each end of this guide. Beneath the roller 7 is a tank or bath 16 in which is a solution which will be more fully described hereafter. On the edge of the tank 16 is supported a smaller roller 17 which is carried by a pivoted arm 18, and is pressed inwardly by a spring 19. The roller 7 may be lowered into the tank, being controlled by the pedal, and when thus lowered and raised again, the felt will be saturated with the solution of the bath. The roller 17 acts upon it, however, to remove all excess moisture so that the felt is rendered moist but not too wet. Above the roller 7 there is supported a pressure pad 20 which is spring-pressed upwardly but which may be pressed down by the pedal 21.

Should, in the judgment of the operator, one side be too intensely colored, he will grasp one of the handles 15 and turn the film in one direction or the other so that the 25 more intensely colored surface will be directed downwardly; at the same time he will, through the agency of the pedals, cause the pressure pad 20 to move downwardly and the roller 7 to move up, so that the 30 roller which is constantly driven by the motor will buff the lower surface of the film. The solution with which the roller is dampened has the effect of releasing from the image some of the dye so as to lessen 35 the color intensity of that surface of the film. The degree of this action may be controlled by the degree of pressure between the roller and the pressure pad above it, and by the degree of dampness of the roller. If 40 the image is one formed by the processes outlined above, and consists of dye precipitated or fixed in place by the acid alum bath, we have found the following correcting or buffering bath to be a useful one: denatured 45 alcohol (90%), 100 parts; ammonia (.880), 1 part.

The ammonia acts upon the dye fixed image to dissolve the precipitated dye and release the dye. As the buffer is merely 50 damp and its action is controlled, the amount of dye released is within the control of the operator. Other alkali baths may be used. We prefer ammonia, however, because this 55 is volatile and leaves on the film no objectionable coating as might be the case with some alkali solutions. The alcohol is not essential but is used to insure quick drying. Since the alcohol and ammonia both evaporate readily and since, moreover, the surface 60 of the film is merely damp, drying in the open air may be sufficient, but I have shown a drying box 11 to insure the drying of the film before it is again rolled up.

It is to be understood that the particular 65 mechanism illustrated above is purely illus-

trative, and the carrying out of our process is in no way dependent upon this mechanism. For this reason, the showing and description have been simplified as far as is consistent with an understanding of the 70 principles of the invention. As a matter of fact, we have found it readily possible merely to pass the film from a supply to a take-up reel past an inspection window and to rub one or the other side of the film with 75 a cloth dampened with the solution, the distance between the reels being made sufficient to dry the film, as it passes through the air. The corrected image may be again examined before being wound up. It is within the 80 scope of our invention to apply this process to dye images formed in other manners, in which case it would, of course, be necessary to adapt the solution to the character of the image so that it would act upon it to release the dye. 85

Having thus described our invention what we claim as new and desire to secure by Letters Patent is:

1. The method of correcting the color 90 ratio of a diapositive consisting of a transparent base with different color records in register upon the opposite faces thereof, which comprises submitting one face only thereof, to the action of a solution which 95 will lessen its color intensity.

2. The method of correcting the color ratio of a diapositive consisting of a transparent support with registering complementary color records upon the opposite 100 faces thereof, each record comprising a colloid layer in which is a dye image, which method consists in submitting that surface which is too intensely colored to the controlled action of a solution which will release the dye. 105

3. The method of correcting the color ratio of a diapositive consisting of a transparent support with registering complementary color records upon the opposite 110 faces thereof, each color record comprising a gelatine film in which is a precipitated dye image, which method consists in submitting that surface which is too intensely colored to the controlled action of a solution 115 which will release the dye.

4. The method of correcting the color ratio of a diapositive consisting of a transparent base with registering complementary color records upon the opposite surfaces thereof, each color record comprising a dyed colloid film in which the dye has been fixed by an acid, which method consists in submitting that surface which is too intensely colored to the controlled action of an alkali solution 120 which will dissolve and release the dye. 125

5. The method of correcting the color ratio of a diapositive consisting of a transparent support with gelatine layers upon the opposite surfaces thereof, in which there are 130

registering images consisting of dyes of complementary color precipitated by the action of an acid alum bath, which method consists of submitting the too intensely colored image to the controlled action of an ammonia solution.

6. In a process of making color motion picture records, comprising the formation in colloid layers upon opposite sides of a transparent support of registered complementary colored dye images, the steps of inspecting such registered dye images to determine which, if either, of the images is too intensely colored and then submitting the too intensely colored image to the controlled action of a solution that will release the dye.

7. In a process of making color motion picture records, comprising the formation in colloid layers upon opposite sides of a transparent support of registered images con-

sisting of dyes of complementary color precipitated by the action of an acid, the steps of inspecting such registered dye images by transmitted light to determine which, if either, of the images is too intensely colored 25 and then submitting the too intensely colored image to the controlled action of a solution that will dissolve and release the dye.

8. The method of correcting the color ratio of a diapositive consisting of a transparent 30 base with dye images in register upon the opposite faces thereof, which comprises submitting one face only thereof to the action of a volatile solution which will release the dye.

Signed at Rochester, New York, this 21st day of March, 1921.

JOHN G. CAPSTAFF.
NEWTON B. GREEN.
